UNITED STATES PATENT OFFICE.

ELMER E. LUTZHOFF, OF ROCKFORD, ILLINOIS, ASSIGNOR TO
H. CLARENCE MARSH, OF ROCKFORD, ILLINOIS.

MITER-BOX.

No. 840,640.

Specification of Letters Patent.

Patented Jan. 8, 1907.

Application filed October 22, 1906. Serial No. 340,093.

To all whom it may concern:

Be it known that I, ELMER E. LUTZHOFF, a citizen of the United States of America, residing at Rockford, in the county of Winnebago and State of Illinois, have invented certain new and useful Improvements in Miter-Boxes, of which the following is a specification.

The object of my invention is to provide means for maintaining the saw of a miter-box in an elevated position therein and out of the way of moldings and other materials being placed therein to be mitered without detaching the saw therefrom; and it consists of certain new and useful features of construction and combinations of parts, all as herein-after fully described, and specifically pointed out in the claims.

Referring to the accompanying drawings, which form a part of this specification, Figure 1 is a top plan view of a miter-box provided with my improvement. Fig. 2 is an elevation of the same. Fig. 3 is a section at the dotted line 3 3 in Fig. 1 of parts there shown. Fig. 4 is a view showing one of the saw-guide pins of the miter-box broken away at the dotted line 4 4 in Fig. 3. Fig. 5 is a detailed view of a spring detached from its saw-guide pin and will be fully described hereinafter.

Like reference characters indicate corresponding parts throughout the several views.

1 is the body of a miter-box provided with clamps 2 and 3 for securing therein materials to be mitered, the former being stationary and the latter movable and actuated by means of the screws 4. The body of the miter-box is equipped with sockets 5, provided with transverse detent bearings 6, which may consist of the upper ends of said sockets or may be in form of transverse recesses, as 7 in Fig. 3, in the inner wall of the same. The sockets 5 are preferably formed integrally with the body 1 of the miter-box by casting them therewith.

9 represents hollow saw-guide pins slidably mounted in the sockets 5 of the miter-box and having transverse openings 10 therein for a purpose to be explained hereinafter.

50 The sockets 5 and saw-guide pins 9 have ver-

tical registering slots 11 and 12 extending therethrough to admit a mitering-saw 13.

14 is a preferably U-shaped spring, formed also preferably of wire, included within each of the hollow saw-guide pins 9 and projecting a detent 15 through the transverse opening 10 therein into engagement with the transverse detent-bearing 6, Fig. 3, of the socket 5.

16 represents vertical adjustable gages to prevent the teeth of the saw from descending low enough to come in contact with the body of the miter-box.

Whenever it is desired to miter a piece of material the operator elevates the saw 13 to the position shown in Fig. 2, when the detents 15 will be forced out into engagement with the detent-bearing 6 (or 7) of the sockets 5 by the action of their springs 14, thereby locking the saw-guide pins 9 and therethrough maintaining said saw in a position that will leave the operator free to place such material between one pair of the clamps 2 and 3 without detaching said saw from its guide-pins. After the material to be mitered has been clamped in the desired position in the miter-box the operator will press upon the back of the saw with sufficient force to cause the detents 15 to spring inward, and thereby release the saw-guide pins 9, which with the saw 13 will then descend until the teeth of the latter rest upon the piece to be mitered.

Having fully described my invention, what I claim as new, and desire to secure by Letters Patent, is—

1. In combination, a socket provided with a transverse detent-bearing, a hollow saw-guide pin slidably mounted therein, a spring included within the hollow saw-guide pin and projecting a detent through the transverse opening in the saw-guide pin into engagement with the detent-bearing of the socket.

2. In combination, a socket provided with a transverse detent-bearing, a hollow saw-guide pin slidably mounted therein, a U-shaped spring included within the hollow saw-guide pin and projecting a detent through the transverse opening therein into engagement with the detent-bearing of the socket.

100

3. In combination, a socket provided with a transverse detent-bearing, a hollow saw-guide pin slidably mounted therein, a **U**-shaped wire spring included within the hollow saw-guide pin and projecting a detent through the transverse opening in said pin into engagement with the transverse detent-bearing of the socket.

In witness whereof I have signed my name to this specification in the presence of two ^{to} subscribing witnesses.

ELMER E. LUTZHOFF.
